[57] CLAIM

The ornamental design for a hat, as shown and described.

DESCRIPTION

FIG. 1 is a side elevation view of a hat showing my new design;

FIG. 2 is a top plan view thereof;

FIG. 3 is a front elevation view thereof;

FIG. 4 is a side elevation view showing a second side thereof;

FIG. 5 is a bottom plan view thereof;

FIG. 6 is a back plan view thereof; and,

FIG. 7 is a side elevation view of FIG. 1, the broken line showing of the human form is for illustrative purposes only and forms no part of the claimed design.
